(57) **CLAIM**

The ornamental design for a tubular packaging for deadbolts, as shown and described.

DESCRIPTION

FIG. 1 is a perspective view of a tubular packaging for a deadbolt in accordance with the present invention;

FIG. 2 is a top plan view of the present invention shown in FIG. 1, it being understood that the bottom plan view is identical thereto;

FIG. 3 is a front elevational view of the present invention shown in FIG. 1;

FIG. 4 is an exploded perspective view in reduced size illustrating the components of the tubular packaging for a deadbolt of the present invention shown in FIG. 1; and, FIG. 5 is a left side view of the present invention shown in FIG. 1, it being understood that the right side is identical thereto.

The broken line showing of the environment is for illustrative purposes only and forms no part of the claimed design.
